UNITED STATES PATENT OFFICE

HUGH R. BYNUM, OF MEMPHIS, TENNESSEE

MANICURE TOOL

Application filed January 19, 1931. Serial No. 509,611.

This invention relates to an abrasive tool primarily for filing finger nails or the like, and is particularly directed to a device of this kind having removable blades which 5 may be used and discarded for sanitary reasons or otherwise.

The objects of this invention are to provide a device for filing finger nails or the like, which comprises a holder or handle 10 member and removable blades therefor; to provide blades for such a holder; and to provide means for securing a blade to the holder.

The means by which the foregoing and other objects are accomplished and the manner of their accomplishment will readily be understood from the following specification on reference to the accompanying drawing, in which:

Fig. 1 is a side elevation of the holder and 20 the blade assembled.

Fig. 2 is a sectional side elevation taken as on the line II—II of Fig. 1.

Fig. 3 is a side elevation showing the opposite side of the device from that shown in 25 Fig. 1.

Fig. 4 is an enlarged section taken on the line IV—IV of Fig. 1.

Figs. 5 and 6 are side views of detached 30 blades of somewhat different shape and/or length.

Referring now to the drawing in which the various parts are indicated by numerals; 35 10 is a blade arcuately curved in cross section which blade is detachably secured to a handle member of holder 11. This handle member carries a clamp which comprises an inner jaw 12, which is secured to the handle, and an outer jaw 13 which is preferably detachable. The outer surface of the inner 40 jaw conforms to the concave surface of the blade and the inner surface of the outer jaw to the convex surface of the blade.

Rotatably secured in and projecting inward from the outer jaw 13 through a suitable aperture in the blade is a threaded pin 45 14 on which a thumb nut 15 is secured as by the pin 15A. This pin screws into the inner jaw 12. Positioned laterally with relation to the pin 14 are positioning pins 16 50 which preferably are integral with the outer

jaw 13 and are adapted to pass through correspondingly located holes in the blade 10 and the inner jaw 12, thus serving to position both the blade and the outer jaw. The hole in the blade for the reception of the clamping screw is designated in Figs. 5 and 6 by the numeral 17 and the holes for the positioning pins by the numerals 18.

The blade is removed by unscrewing the pin 14 and removing the jaw 13 thus freeing the blade for removal and permitting a new one to be put in place and thereafter to be secured.

As seen in Fig. 4, the holes in the blade for the reception of the positioning pins may be slightly elongated laterally to minimize binding in the removal or replacing of the blade.

Preferably the blade is substantially rectangular in form except that the outer end 19 is rounded or curved although as shown in Fig. 5, this may not be done. The blade is arcuate in cross section and conforms to the curvature of the jaws of the holder, but this curvature may be secured by the clamping action of the jaws should it be so desired.

The blade is a thin sheet of material which may be metal, but preferably is of fiber board, hard paper, celluloid or the like material possessing a certain amount of stiffness so that especially in its curved shape it is substantially rigid under the uses for which it is designed. If of metal, a surface similar to the ordinary nail file may be formed directly in the metal but preferably the abrasive surface is formed by coating the sheet material with an abrasive. Under usual conditions the concave side is always coated with abrasive, and preferably the convex surface and the edges of the blade as well are similarly covered.

It is proposed to make an inexpensive blade which may be renewed as frequently as conditions warrant. Where used by manicurists, 95 chiropodists or other professional operators, a new blade may be used for each individual.

In using the blade the side surfaces may be used in dressing the ends of the nails or otherwise as desired and the edges of the blade in dressing the 100 cuticle at the base of the nails.

Having described my invention, what I claim is:

1. An abrasive tool, comprising a holder and cooperating abrasive blade therefor, said holder comprising a handle having at one end a jaw arcuate in transverse section, a complementary arcuate jaw detached therefrom, and a clamping screw rotatably secured in said detached jaw and adapted to pass through said blade and engage with threads in the other jaw, one of said jaws having projecting pins and the other thereof having complementary holes for the reception of said pins.
2. An abrasive tool, comprising a holder and cooperating abrasive blade therefor, said holder comprising a handle at one end, a jaw arcuate in transverse section, a complementary jaw detached therefrom, and a clamping screw rotatably secured in said detached jaw, and adapted to pass through said blade and engage with threads in the other jaw, said detached jaw having projecting pins and the other of said jaws having complementary holes for the reception of said pins.

In testimony whereof I hereunto affix my signature.

HUGH R. BYNUM.
